(No. Model.)

J. M. GRIEST.

TUCK CREASING OR MARKING ATTACHMENT FOR SEWING MACHINES.

No. 394,968.

Patented Dec. 25, 1888.

UNITED STATES PATENT OFFICE.

JOHN M. GRIEST, OF CHICAGO, ILLINOIS, ASSIGNOR TO THE SINGER MANUFACTURING COMPANY OF NEW JERSEY.

TUCK CREEASING OR MARKING ATTACHMENT FOR SEWING-MACHINES.

SPECIFICATION forming part of Letters Patent No. 394,968, dated December 25, 1888.

(Application filed December 27, 1887. Serial No. 259,093. (No model.)

To all whom it may concern:

Be it known that I, JOHN M. GRIEST, a citizen of the United States, residing at Chicago, in the county of Cook and State of Illinois, have invented certain new and useful Improvements in Tuck Creasers or Markers for Sewing-Machines, of which the following is a specification, reference being had therein to the accompanying drawings.

10 The object of my invention is to provide a convenient, strong, and substantial tuck creasing or marking attachment for sewing-machines, in which the creasing is effected by two pinching-levers operating on the goods on opposite sides of an upwardly-projecting lip on the base-plate or lower arm of the attachment.

15 In the drawings, Figure 1 is a perspective view of my improved attachment. Fig. 2 is a plan view of the same. Fig. 3 is a longitudinal section on line 3 3, Fig. 2, with the marking-lever depressed. Fig. 4 is a cross-section on line 4 4, Fig. 2. Fig. 5 is a detail view to show the connection between the operating-lever 25 and the marker-lever. Fig. 6 is a detail section on line 6 6, Fig. 2.

20 A denotes a support or bracket, the upturned portion *a* of which is provided with a slotted horizontal part, *a'*, adapted to be secured to an attachment-holding bar such as is shown by my application, Serial No. 259,090, filed simultaneously herewith.

25 B is the body-bar of the attachment, passing through the support A and having its forward end, *b*, flattened and provided with an upwardly-projecting creasing-lip, *b'*, the rear end *b²* of the said bar being turned upward and backward and bored to form a socket for the reception of the rear end *c* of 30 the marker-carrying lever C, to the forward end of which latter are pivoted two small pinching or creasing levers, *c'*, having lugs *c²*, connected by a retracting-spring, *c³*. A stop, *c⁴*, formed on the part of the lever C to 35 which the pinching-levers are pivoted, is arranged to be engaged by the tail portions *c⁵* of the said pinching-levers, and thus limit the return movements thereof effected by the spring *c³*.

40 D is the operating-lever, pivoted to a small

post, *a²*, on the bracket or support A, the said lever having a lug, *d*, arranged to be engaged by the lower end of the needle-bar of the machine. The lever D is provided at its forward end with perforated lugs *d' d²*, through which passes the longer arm of a hook, *e*, the shorter arm of which impinges against the upper side of the marker-carrying lever C. A spiral spring, *e'*, interposed between a pin, *e²*, entering the longer arm of the hook *e*, and the lug *d²*, forms a yielding connection between the said hook and the lever D, so that if the shorter arm of the said hook should force the marker-carrying lever or arm downward as far as it is desirable for it to go before the needle-bar should have reached the lowest point of its descent the spring *e'* will be compressed, and a sudden shock or jar will thus be prevented.

45 The hook *e* is free to be turned in the lugs *d' d²* of the operating-lever D, so that if it is desired to disconnect the said operating-lever from the marker-carrying lever C to suspend the movements of the latter it is only necessary to turn the said hook to the position 50 shown by dotted lines in Fig. 3, when it will be entirely clear of the said lever C. A torsional spring, *b³*, on the rear end *b²* of the bar B serves to lift the lever C after it has been depressed.

55 The rear end *c* of the lever C is preferably held in a socket at the end *b²* of the bar B by a pin, *f*, which in the present instance is merely the upturned end of a small rod, F, the forward end of which extends over the lip 60 *b'*, and thus serves as a slight presser to hold the passing fabric on the said lip. The pin *f* fits rather loosely in the hole in the end *c* of the lever C, so that the said lever will be free to move downward when depressed by the 65 needle-bar, but the said pin fits closely enough in said hole to serve as a stop to limit the upward movement of the said lever when the latter is raised by the spring *c³*.

70 G is an edge guide secured to a bar, *g*, passing through the support or bracket A and adjustable therein, the said edge guide being 75 steadied by the bar B, which passes freely through said guide. The bar B is also free to be adjusted through the support or bracket 80

A when not clamped thereto, so that the upper and lower creasing devices, which are both movable with said bar, may be adjusted from or toward the needle of the machine to 5 vary the width of the tucks made by folding the fabric on the crease produced by the said creasing devices, the said support or bracket being, of course, stationary relative to the line of the stitches made by the machine. 10 The bars B and g, which are preferably provided with flattened lower faces, are secured to the support or bracket A by a clamping-plate, H, provided with threaded pins h, extending up through the said support or 15 bracket A and receiving set-nuts h', by which the clamping-plate may be forced upward against the lower flattened faces of the said bars to hold them in place.

When the creasing or marking attachment 20 is secured in place on a sewing-machine and the machine set in motion, a vibrating movement will be imparted to the marker-carrying lever by the needle-bar of the machine and the retracting-spring c³. When the pinching-levers c' strike the flattened forward end, b, 25 of the bar B on opposite sides of the lip b', they will be forced toward each other, pinching the fabric lying on said lip to form a mark or crease on which the said fabric will be 30 folded to form the next tuck parallel with the one being sewed.

I claim—

1. In a tuck creaser or marker for sewing-machines, the combination, with a lower creasing device and a marker-carrying arm or lever, of two independent pinching or creasing levers pivoted to the forward end of the said marker-carrying lever, a single retracting-spring for the said pinching-levers, and means 35 for operating the said marker-carrying lever.
2. In a tuck-creaser for sewing-machines, the combination, with the bracket or support A, of the body-bar B, having the flattened end b, provided with the lip b' and the rearwardly-45 turned hollow end b², the marker-carrying lever C, pivoted in the said hollow end, the two

independent pinching or creasing levers c', the retracting-springs c³ and b³, and the operating-lever D.

3. In a tuck creaser or marker for sewing-machines, the combination, with the lower creasing device and the marker-carrying lever C, of the operating-lever D, having the perforated lugs d' d², the reversible hook e, one arm of which passes freely through said 55 lugs and the other arm of which impinges against the said lever C, the spiral spring e', and the pin e².

4. In a tuck creaser or marker for sewing-machines, the combination, with the body-bar B, having a creasing-lip at its forward end and having at its rear end a longitudinally-socketed portion, b², of the marking-lever C, the rear end, c, of which has a bearing in the said 60 socketed portion b², the spring-rod F, having an upturned rear end to form a pin which retains the said end c in its socket, and having its forward end extended over the said creasing-lip to serve as a presser, and means for 65 operating the said lever C.

5. In a tuck creaser or marker for sewing-machines, the combination, with the creasing devices and the bracket or support A, of the bars B and g, passing through said support, the edge guide G, steadied by the said bar B, 70 which passes through the said guide, the clamping-plate H, having the threaded pins h, and the set-nuts h'.

6. In a tuck creaser or marker for sewing-machines, the combination, with the marking-lever C and its lifting-spring, of the operating-lever D, carrying at its forward end the reversible hook e to impinge against the said 75 lever C, and the support or bracket A, having the post A², to which the rear end of the said 80 lever D is pivoted.

In testimony whereof I affix my signature in presence of two witnesses.

JOHN M. GRIEST.

Witnesses:

HENRY CALVER,
EWELL A. DICK.
